TRAILER COACH

Myron C. Poole, Elwood, Ind., assignor to Holan
Engineering Co., Inc., Elwood, Ind.

Application January 23, 1953, Serial No. 23,270

Term of patent 14 years

(Cl. D14—3)

To all whom it may concern:

Be it known that I, Myron C. Poole, a citizen of the United States of America, residing at Elwood, in the county of Madison and State of Indiana, have invented a new, original, and ornamental Design for a Trailer Coach, of which the following is a specification, reference being had to the accompanying drawing, forming a part thereof.

In the drawing:

Fig. 1 is a perspective view looking from the rear end of the left hand side of the trailer coach, embodying my new design.

Fig. 2 is a view similar to Fig. 1 looking from the front end of the right hand side of the trailer.

I claim:

The ornamental design for a trailer coach, as shown.

MYRON C. POOLE.
